UNITED STATES PATENT OFFICE.

JAMES D. GARVEY, OF CHICAGO, ILLINOIS.

BRUSH.

Application filed March 10, 1922. Serial No. 542,800.

To all whom it may concern:

Be it known that I, JAMES D. GARVEY, a citizen of the United States, and a resident of Chicago, in the county of Cook and State 5 of Illinois, have invented certain new and useful Improvements in Brushes, of which the following is a description, reference being had to the accompanying drawings, which form a part of my specification.

10 My invention relates to a hand type of fountain brush, wherein a reservoir or font for containing the fluid may be located at a distance removed from the brush proper, with the flow of fluid from the reservoir or 15 font being under the control of the operator; the present invention pertaining more particularly to the brush proper adapted for different uses and to be employed in connection with a reservoir or container of the type 20 more particularly disclosed in my co-pending application, Serial No. 437,525.

The objects and advantages of my invention will be more fully comprehended from the detailed description of the accompanying 25 drawings, wherein:

Figure 1 is a side elevation of my improved brush, shown in connection with a reservoir (of which only a portion and its connecting conduit is shown) of the type 30 disclosed in my co-pending application.

Figure 2 is a sectional view taken on the offset line 2—2 of Figure 1 looking in the direction of the arrows.

Figure 3 is a detail sectional view taken 35 on the line 3—3 of Figure 2 looking in the direction of the arrows.

Figure 4 is a vertical sectional view taken on the line 4—4 of Figure 1 looking in the direction of the arrows.

40 My improved brushes, which are adapted for washing, polishing and the like, are intended for use in connection with a fluid-holding container or reservoir of a construction which will permit the same being easily 45 transported or carried; while the flow of fluid may be readily controlled by the finger or thumb of the hand which holds the container or reservoir; the fluid being intended to be conveyed by means of a flexible conduit 50 or tube to an aperture, located preferably somewhat centrally in the main body or back of the brush proper.

In the exemplification of the invention, as 55 disclosed in the first four figures of the drawings, a type of brush is shown which is more especially adapted for washing or polishing

furniture, automobile bodies and the like and the brush comprises a pair of side frame members 10, 10, preferably of wood or other suitable material. The side frame members 60 are preferably shown semi-circular in cross-section for the sake of appearance and finish, with the flat surfaces of said side frame members disposed vertically and toward each other. These surfaces are provided at suitable points with apertures or sockets to receive transversely disposed pins or short rods 11 which are also preferably composed of wood for the sake of lightness. Any suitable number of pins or rods are employed, in keeping with the size of the brush, 70 that is in keeping with the length of the side frame members; with the pins or rods preferably arranged at suitable and equidistant apart. The side frame members 10 75 are secured together by means of a metallic plate or back 12; the longitudinal edges whereof are flanged, preferably in an upward direction, as shown at 13. The plate or back 12 is disposed in a plane slightly below that of the upper edges of the side frame members 10, 10, in order that the flanges 13 of the back or plate 12 may extend flush 80 with the flat surfaces of the side frame members 10 to which the flanges are secured in 85 any suitable manner as for example by means of the screws 14.

The ends of the plate or back 12 are shown bent downwardly at 15 in Figure 3, preferably to a point slightly beneath the lower 90 edges of the side frame members 10, thereby overlapping and somewhat protecting the cord or wire shown at 16 which is wound about the strands of yarn, or suitable thread, indicated at 17 which constitutes the body 95 of the brush. The body of the brush consists of short strands or portions of wool yarn or suitable thread cut to predetermined lengths and arranged or looped about the transverse pins or rods 11 in the manner 100 more clearly shown in Figures 3 and 4; that is to say the yarn or thread is grouped to completely fill the rods or pins 11 intermediate of the side frame members 10; with the respective strands arranged to be substantially 105 of equal length.

After the strands of yarn or thread have been placed about the rods or pins 10, I then secure them against displacement by binding the same with the cord or wire as shown at 110 16; the cord or wire being wound about the strands of yarn or thread at a point slightly

beneath the pins or rods 11 as shown in Figures 3 and 4.

With this construction, it is apparent that the yarn or strands of wool or thread may be readily removed, when occasion requires, by simply removing the binding cord or wire 16 and if necessary removing top plate or back member 12.

The top plate or back 12 is provided with a suitable handle as indicated at 18, which is riveted or otherwise suitably secured thereto; and the plate or back 12, at a suitable point intermediate of its ends, preferably beneath the handle 18, is provided with an opening 15 as shown at 19 in Figure 3 which is adapted to receive the end of a flexible conduit or tube 20, which latter leads from the valved outlet of the container portion of the fountain brush.

20 The brush thus far described is intended more especially for washing furniture or other articles having a polished surface. The brush described is also adapted for use, after the washing operation has been completed, 25 as a polishing brush in connection with any suitable polishing fluid with which the container portion of the fountain brush may be provided. I prefer, when the brush is intended to be used for polishing, that it be 30 provided with a piece of chamois as at 21 adapted to fit onto and somewhat about the lower ends of the yarn or thread portion 17 of the brush. As shown in the drawings, the chamois is preferably provided with suitable 35 perforations 22, to permit the polishing fluid, discharged by the conduit through the back of the brush, to flow therethrough. The longitudinal edges of the chamois 21 are preferably eyeletted or perforated for the 40 passage of a suitable cord or flexible element 23 whereby the chamois is secured to the side members 10 of the brush. The side members, at suitable points, are shown provided with screw-eyes or hooks as at 24 which may be 45 provided with small metallic rings as at 25 through which the flexible element or cord 23 is passed and thereby secured in place; the cord or flexible element 23 being preferably arranged in the laced or zig-zag manner 50 shown in Figure 1, namely by having one end of the cord or flexible element secured to the chamois adjacent one end of the brush and thence passed upwardly through the ring 25 immediately thereabove, thence 55 downwardly through the second hole in the longitudinal edge of the chamois and thence upwardly in the staggered manner through the second ring and so on, with the opposite end of the cord or flexible element secured to the ring at the opposite end of the brush. When the brush 60 is used for polishing purposes the operator may readily supply the same with the desired quantity of polishing fluid by operating a suitable valve in the container. The 65

flexible conduit 20 is preferably inserted through the opening 19 in the back of the brush sufficiently to prevent its accidental withdrawal; and if desired, it is evident that any suitable means may be employed for fastening the tube in place.

I have shown and described what I believe to be the simplest and best embodiments of my invention adapted to the uses and purposes for which the invention is intended; having described the same in terms employed merely as terms of description and not as terms of limitation, as structural modifications are possible and may be made without, however, departing from the spirit of my invention.

What I claim and wish to secure by Letters Patent is:—

1. A brush of the character described, comprising a back provided with a conduit-receiving aperture and side members, rods disposed transversely of the back between said side members, strands of yarn or thread looped about said rods intermediate of the side members, and means whereby said strands are secured in place.

2. A brush of the character described, comprising a back provided with an aperture, side frame members secured to said back to depend beneath the same, a plurality of rods arranged in spaced relation disposed transversely of the back and secured to the side frame members, strands of yarn or cord looped about said rods, and tie means disposed about the strands at a point beneath said rods whereby the strands are held in place.

3. A brush of the character described, comprising a sheet metal back provided with an aperture to receive the end of a flexible fluid-conveying conduit, side frame members removably secured to said metallic back so as to depend beneath the same, a plurality of rods arranged in predetermined spaced relation transversely beneath the back with their ends removably secured in said side frame members, strands of yarn or cord looped over said rods, a binding element disposed about said strands adjacent to said side frame members, an eyeletted sheet of chamois covering the ends of said strands, and means whereby said sheet of chamois is removably secured to said frame members.

4. A brush of the character described, composed of a metallic back apertured to receive the end of a fluid-containing conduit and having flanged longitudinal sides, side members removably secured to the flanged sides, rods disposed in spaced relation between the side members, fluid-retaining means disposed about said rods, and a binding element disposed about said last mentioned means whereby the same are removably secured to the rods.

5. A brush of the character described,

comprising a sheet metal back apertured to receive the end of a flexible fluid-conveying conduit, side frame members secured to said metallic back so as to depend therefrom, the outer sides of the side frame members being provided with a plurality of tie-element receiving members, a plurality of rods arranged in spaced relation beneath the back with their ends secured in said side frame members, strands of yarn or cord looped over the respective rods, a binding element

disposed about said strands for removably securing the same in place, a sheet of chamois covering the ends of said strands, and a binding element removably laced intermediate of the chamois and the tie-receiving members on the side frame members. 15
